UNITED STATES PATENT OFFICE.

WILLIAM O. NICHOLS, OF LYNN, MASSACHUSETTS.

LAST.

SPECIFICATION forming part of Letters Patent No. 254,150, dated February 28, 1882.

Application filed December 8, 1881. (No model.)

To all whom it may concern:

Be it known that I, WM. O. NICHOLS, a citizen of the United States, residing at Lynn, in the county of Essex and Commonwealth of Massachusetts, have invented certain new and useful Improvements in Lasts to be Used in Boots and Shoes, of which the following, taken in connection with the accompanying drawings, is a specification.

10 In the process of manufacturing boots and shoes as the art is now practiced it often happens that the workman, in order to maintain a sufficiently firm hold of the shoe, is compelled to fix his grasp upon the upper leather or 15 vamps, so that these parts not unfrequently become badly crushed by the grip of the operator's hand.

It is the object of this invention to provide a device to be inserted within the boot or shoe, 20 without materially increasing the weight thereof, which shall keep the vamp sufficiently rounded out to prevent its being unduly crushed by any ordinary grip of the workman.

The invention consists in a concavo-convex 25 shell, or mock last, having the conformation shown in the drawings, to be constructed and used as hereinafter more fully described.

Figure 1 of the drawings is a plan view, showing the form into which the material is 30 cut before being molded. Fig. 2 is a perspective view, showing the form of the article after being molded.

A piece of thin sole-leather or leather-board is first cut into the shape shown in Fig. 1. It 35 is then given the conformation shown in Fig. 2 by any obvious process of molding. The size of the article should be determined according to the size of the boot or shoe in which it is intended for use. I prefer to make it 40 large enough to require compression of the sides in order to get it into the boot or shoe, so that its resiliency or tendency to expand when in the shoe shall be sufficient to keep the vamp fully rounded out.

Any requisite degree of resiliency may be 45 obtained by due regard to the thickness and nature of the material used.

An article made in this manner will be sufficiently flexible to allow the vamp to be depressed or sprung away from the sole-edge 50 whenever occasion requires it. To examine or work upon the rand it will too be sufficiently resilient to counteract the ordinary grip of the operator, so as to prevent the upper or vamp from becoming unduly jammed or crushed. I 55 do not, however, confine myself to the use of the material named, for it is evident that the article may as well be made of rubber, gutta-percha, wood, pasteboard, sheet metal, and many other obvious substances which admit of 60 molding, substantially as described. Neither do I limit myself to an article having lateral flexibility or resiliency, for a stiff shell having the desired conformation will be equally useful in many cases; but 65

I claim—

1. As a new article of manufacture, the bottomless shell or expander for a boot or shoe, having flexible or elastic sides.

2. An improved device for expanding the 70 upper of a boot or shoe, for the purpose set forth, formed from a single piece or blank bent into shape and having free spring sides, all substantially as set forth.

3. An improved device for expanding the 75 upper of boots or shoes, consisting of a hollow body portion of the contour of the front top portion of a last, terminating in rearwardly-extending spring side pieces having free ends, all substantially as shown, for the purposes set 80 forth.

WILLIAM O. NICHOLS.
